UNITED STATES PATENT OFFICE.

EPHRAIM H. FENTON, OF KANSAS CITY, MISSOURI.

GRINDING-MACHINE.

SPECIFICATION forming part of Letters Patent No. 428,204, dated May 20, 1890.

Application filed December 16, 1889. Serial No. 338,916. (No model.)

To all whom it may concern:

Be it known that I, EPHRAIM H. FENTON, a citizen of the United States, residing at Kansas City, in the county of Jackson and State 5 of Missouri, have invented certain new and useful Improvements in Grinding-Machines; and I do hereby declare that the following is a full, clear, and exact description of the invention, such as will enable others skilled in the 10 art to which it appertains to make and use the same, reference being had to the accompanying drawings, forming a part of this specification.

The object of my invention is to communicate automatically from the driving-shaft a 15 vibratory movement to the table in line with the grinding-tool in grinding-machines and also regulate the vibrations of the table in such a manner that the distance traversed in 20 said vibrations past the grinding-tool may be increased and diminished.

My invention further consists in the novel construction and combination of parts, which will first be fully described, and specifically 25 pointed out in the claims.

In the drawings, Figure 1 is a view in perspective of my improved grinding-machine, taken from the side, which is provided with the pitman for operating the table, an end 30 portion of which table is broken away to show the pivoted table-support. Fig. 2 is a side elevation of the table, showing its angle of movement in dotted lines. Fig. 3 is a view in perspective of the pitman for operating the 35 table. Fig. 4 is a side view in detail of the adjustable crank on the shaft. Fig. 5 is an edge view of the adjustable portion of the crank, seen at right angles to its position in Fig. 4, showing the crank-wrist.

40 Similar letters of reference indicate corresponding parts in all the figures.

In the construction of my improved machine A represents a flat rectangular-shaped bed. Upon the bed A in the direction of one 45 end is secured fixedly the lower end portion of a standard B, the other end of which is forked at b b. Through the forked ends b b in a horizontal direction are made the perforations b' b', and through said perforations is 50 introduced one end portion of a driving-shaft c, which is screw-threaded a short distance at c'. Upon the other end portion of shaft c is

mounted an external annular cog-wheel C, which is made of the proper dimensions to constitute the tool-driving wheel, and is placed 55 close in position to and at one side of the standard B. Upon the wheel C is secured a handle c^x.

A tool-carrying frame D is constructed, which consists of two parallel arms d d' of a 60 suitable length, which are connected rigidly by transverse bars d² d², which are arranged between the opposite ends of said frame. The opposite portions or arms d d' at one end of the frame D are made to fit against the 65 respective outer side portions of the forked ends b b of standard B, and are perforated in a transverse direction at d³ to receive and vibrate freely upon the shaft c, which extends through said arms. The frame D extends 70 from the shaft c radially a short distance beyond the periphery of the driving-wheel C. On the side of the contiguous portion of the wheel C to the arm d' of frame D, and attached rigidly to the hub of said wheel C, is 75 a sleeve c², which extends to the side of arm d', and upon the screw-threaded end of the shaft c is fitted a nut c³, which nut and sleeve prevent any lateral movement of the wheel C. Through the sleeve c² and the shaft 80 c is made in a transverse direction a registering perforation c⁴, through which perforation is inserted a pin or key c⁵. In the other end of frame D and the arms d d' than those connected with the shaft c are attached the journal-boxes d⁴ d⁴, and journaled in a horizontal position in said journal-boxes is a mandrel E, one end of which mandrel extends to a point 85 beyond the inner side of and in line with the periphery of said wheel C, and upon said end 90 of the mandrel, opposite to and meshing with the cogs on said wheel C, is keyed a gear e. Upon the mandrel E, between the parallel arms d d' of frame D, is fitted rigidly, so as to turn therewith, a grinding-disk F, composed of emery or other suitable grinding material, which said disk corresponds in shape to two truncated cones joined at their bases and adapted more particularly for sharpening mower and reaper knives. The form of 100 the tool, however, may be changed to accommodate the conformation of the tool to be ground. To receive the extended disk F between the vibrating end portions of the frame

D a portion of the said arm d' is bent in a curved line of direction and extended laterally from the arm d the required distance.

To the extreme vibrating end portion of 5 the frame D, a short distance from the journal-boxes d^4 , and extending in a curved direction from arm d to arm d' , is attached rigidly a brace-bar d^5 , and extending laterally from the brace-bar beyond the line of the 10 said vibrating end portion of said frame D is a handle d^6 .

Upon the other end portion of the bed A from that having standard B, and which is in front of the grinding-disk F, is mounted a vibrating table G, parallel with the shaft c. To support the table G an adjustable plate g of narrow width is extended in a horizontal direction across the said bed A, at either end of which plate are attached the lugs $g' g^2 g^3 g^2$.

20 In a transverse direction through plate g, in line with and near the sides of lugs $g' g^2$, which are directly opposite each other, are made the slots $g^3 g^2$. Through the bed A are inserted the bolts $g^4 g^4$, one end of each of 25 which extends in a vertical direction through the slots $g^3 g^2$, and are screw-threaded and provided with the nuts $g^5 g^5$. Between the lugs $g' g^2 g^3 g^2$ is pivoted the lower end portion of the single legs or supports $g^6 g^6$, and to the 30 upper end portion of said supports is attached rigidly the vibrating table G. In the central and side portion of the table G, opposite to and in line with the disk F, is made a V-shaped opening g^8 , corresponding to that between 35 the separate teeth in the knives of a mower or reaper. Extending a short distance from each end of table E in a horizontal direction, and from the side other than that provided with the V-shaped slot, are the supports $g^7 g^7$, and upon the outer end portion of each support are pivoted double-armed levers $g^8 g^8$, which are arranged in position a short distance above and extend over the top portion of the table G, so as to pass in a circuit 40 over and hold the knives in position upon said table, the rigidly-connected arms $g^9 g^9$ of which levers extend in an opposite direction and are elevated in position above the line of said levers.

45 To the upper end portion of the vibrating legs g^6 of the table G, which is on the other side of the machine from that having wheel C, and on the side toward the grinding-disk F, is attached the lower end portion of an 50 arm H, which extends in an upward curved direction over the side and to a point above table G in a vertical line with the said leg g^6 . The upper end portion of the arm H is made flat at h and perforated in a transverse direction. A portion c^6 of the shaft c on the 55 standard B, between the nut c^8 and the arm d' of frame D, is extended in length and made square in form. (See Figs. 4 and 5.) A crank I is then made, one portion i of which 60 is made flat of a suitable length, and through said plate is made a longitudinal slot i' , which is of a sufficient width to fit over the square

portion c^6 of shaft c and slide thereon. The other portion i^2 of the crank is made circular in form, and a short distance from the portion i of the crank, from which it extends at right angles, the outer end of said portion i^2 is reduced in diameter to form a wrist i^3 . The slotted portion i of the crank is then fitted over the square portion of the shaft c and the 75 nut c^3 turned on said shaft against the said portion i of the crank, so as to hold the crank adjustably in position.

To the upper end portion of the arm H are connected the forked ends $k k$ of a lever-arm 80 or pitman K, which is perforated at k , so as to register with the transverse perforation in the portion h of the arm H, and through said perforation is inserted a split pin or key k^2 . The other end of the pitman K extends to 85 the wrist i^3 of crank I and is perforated at k^4 in a transverse direction, so as to fit over and turn freely on said wrist.

Between the crank I and the arm H the pitman K is bent laterally at an angle, so as 90 to form a double curve, and thus be removed from the path of the grinding-tool. Through the wrist i^3 is made outside of the pitman K a transverse perforation, through which is inserted a split pin or key k^3 .

95 In the operation of my improved machine the tool-frame D is held by the hand above the plane of the table, and the mower-knives laid horizontally upon the table in such a position as to bring the contiguous portions of 100 adjacent teeth in line with the V-shaped opening G. The levers g^8 are then swiveled in position by means of the arms g^9 , so as to rest upon the knives upon the table and prevent an upward recoil movement. The grinding tool or wheel F is then placed upon the 105 teeth of the mower-knives. The wheel C is then rotated by means of the handle c^5 , and an accelerated movement communicated to the gear e and also to the grinding-tool. In 110 the same movement of the wheel C the crank I upon shaft c turns therewith, and the movement is communicated by the pitman K to the table, which is vibrated to and fro beneath the grinding-tool and the knives thereon 115 immediately in the path of the said tool. In this manner the entire length of the teeth upon a cutter-bar of a mower or reaper is ground uniformly, and the change of position of the grinding-tool accomplished automatically in the rotation of the driving-wheel. When it is desired to vibrate the table with 120 rapidity, and thus present the length of surface of the teeth more frequently to the action of the grinding-tool, the nut c^3 is turned, so as to 125 permit the adjustment of the slotted plate i , and the portion i^2 of said crank brought nearer in position to the end of shaft c, thus reducing the length and circuit of rotation of the crank. When plate i is adjusted in 130 an opposite direction, so as to increase the distance between the portion i^2 of the crank and the end of shaft c, the vibrations of the table are slower, though the speed of the

driving-wheel may be increased and the angle of the table adapted to knives varying in length as well as enabling the grinding to be accomplished more gradually and in slower degrees 5 the entire length of the teeth of the knives. When it is desired to adjust the position of table G farther beneath the grinding-tool, the nuts g^5 on the bolts g^4 , which hold the plate g upon the bed A, are released and the said 10 plate pushed forward in the direction of the standard B, thereby changing the position of the legs g^6 in relation to the fixed position of the grinding-tool when in rotation, and thereby and in connection with the adjustment of 15 the pitman connected with the table enable the grinding to be confined to a short portion of the teeth of the mower-knives and the teeth vibrated at the same time with rapidity, so that various forms of knives are adapted 20 to be sharpened, according to their peculiar shape and degree of hardness of the material of which they consist.

Having fully described my invention, what I now claim as new, and desire to secure by 25 Letters Patent, is—

1. In a grinding-machine having a driving-shaft at one end of said machine and a vibrating table having vibrating standards at the other, the combination, with said shaft 30 and table, of a pitman, and a crank connected with said pitman and said shaft and adjustable in said shaft, and a support for said standards adjustable in the line of direction of said pitman, substantially as and for the 35 purpose described.

2. In a grinding-machine, the combination, with a suitable standard, of a driving-wheel having a driving-shaft provided with a crank on said standard, a vibrating tool-holder or

frame pivotally attached at one end to said standard and having a rotating grinding-tool at its other end provided with suitable gearing connected with said driving-wheel, a vibrating table beneath said grinding-tool, and a pitman connected with the crank on said shaft and said table, for the purpose described. 40

3. In a grinding-machine, the combination, with a suitable standard, of a driving-wheel having a driving-shaft, a vibrating tool-holder or frame pivotally attached at one end to said standard and having a rotary grinding-tool at its other end provided with suitable gearing connected with said driving-wheel, a vibrating table beneath said grinding-tool, a pitman 50 connected at one end with said table and a crank connected with the other end of said pitman and adjustably connected with said driving-shaft, substantially as and for the purpose described. 55

4. In a grinding-machine, the combination, with a suitable standard at one end of said machine, of a driving-wheel having a driving-shaft provided with a crank, a tool-supporting table at the other end of said machine, a 60 pitman connected with said table and said crank, a vibrating tool-holder or frame pivotally attached at one end to said standard and having a rotary grinding-tool at its other end and provided with suitable gearing connected with said driving-wheel, and supports for said vibrating table adjustable in the direction of said standard, for the purpose described. 70
